INFLATED PLAY HORSE

Robert E. Clarke, 450 Trappe Road, Dundalk, Md.

Filed Dec. 30, 1959, Ser. No. 58,861

Term of patent 7 years

(Cl. D34—15)

I claim:

The ornamental design for an inflated play horse, as shown and described.
